The ornamental design for a polyhedron sensor enclosure, as shown and described.

DESCRIPTION

FIG. 1 is a perspective view of a closed polyhedron sensor enclosure.

FIG. 2 is a front view thereof;

FIG. 3 is a back view thereof;

FIG. 4 is a perspective view thereof indicating a cross section;

FIG. 5 is a cross sectional view of the interior space of a closed polyhedron sensor enclosure.

FIG. 6 is a perspective view of a partially closed polyhedron sensor enclosure.

FIG. 7 is a perspective view of an opened polyhedron sensor enclosure.

FIG. 8 is a first side view thereof;

FIG. 9 is a second side view thereof;

FIG. 10 is a top view thereof; and,

FIG. 11 is a bottom view thereof.

The broken lines represent environment and form no part of the claim.
